FASTENER

Alfred Boenecke, Berlin, Germany

Application August 30, 1935, Serial No. 38,647.
In Germany September 8, 1934

3 Claims. (Cl. 292—302)

This invention relates to a fastener, which may be used for all kinds of articles, for example for handbags, garments or the like.

The fastener comprises two portions, viz., a male portion and a female portion. The rigid outer edges of the male and female portions are bent over in hook-like fashion, and the closing of the fastener takes place by the hooked edge of the male portion snapping from below into the hooked edge of the female portion.

The invention consists in the fact that the effective line of engagement formed by the hooked edges of the male and female portions is always greater in length than the width of the fastener.

In this manner it is accomplished that the fastener is capable of withstanding considerable tensile stresses without being damaged or without the same being opened unintentionally.

The invention will be described more fully with reference to the accompanying drawing, which illustrates a possible form of embodiment of the invention.

Fig. 1 is a section through the fastener along the line I—I in Fig. 2.

Fig. 2 is a plan view of the fastener, whilst

Fig. 3 is a section through the fastener along the line III—III in Fig. 1.

Figs. 4, 5 and 6 are plan views of different fasteners showing that the fastener may be furnished with many different forms according to its particular use.

In all of the figures of the drawing the fastener is shown in its closed condition.

The fastener comprises two parts, viz., the male portion 3 and the female portion 5. The male portion 3 is connected with that part 4 of the article which is to be secured. If, for example, the article is a lady's bag, the part 4 bearing the male portion 3 of the fastener would be the flap of the bag, and the female portion 5 would be situated at a suitable point of the bag itself to enable the flap to be closed.

The male portion 3 consists of the outer edge 1, which is bent in hook-like fashion, the tongue 2 and the upper portion 8, which in the embodiment according to Figs. 1 to 3 is in the form of a button. The single parts of the male section of the fastener may be secured in simple fashion 50 to the article 4 by rivets.

The female portion 5 has an outer edge 6 which is bent in hook-like fashion in opposition to the edge 1, so that the two edges 1 and 6 are capable of readily engaging. The leaf spring 8 of the female portion 5 serves to press the two

parts 3 and 5 tightly together in the closed condition of the fastener. The female portion 5 may have the form shown in Fig. 2, and is secured to the article in simple fashion by means of rivets.

Upon the closing of the fastener the tongue 2 of the male portion 3 is introduced in such fashion into the female portion 5 in opposition to the pressure of the spring 8 that the edge 1 engages behind the edge 6, the fastener then being closed. 10 The ends 15 of the edge 6 are bevelled, so that the introduction of the male portion 3 takes place in sliding fashion without obstruction. The actual engagement occurs along the two semi-circular edges 1 and 6, the fastener being flat, as 15 the part 3 does not rest on the part 5. In place of the semi-circular form there may also be employed a discontinuous line. In every case, however, the line of engagement between the edges 1 and 6 is always greater in length than the width 20 of the fastener.

Opening of the fastener is performed in simple manner by pressing one finger against the upper portion 8. In this way a counter-pressure is exerted on the spring 8 such that the front end 7 25 of the spring 8 assumes the position shown in Fig. 1 in broken lines, allowing the two edges 1 and 6 to disengage. With the finger still resting on the upper portion 8 the male portion 3 is thereupon withdrawn and thus released from the female portion 5.

In order that the finger may obtain a proper hold on the part 8 the surface of the latter may be milled, grooved or raised.

The fastener may include a key casing 11 in 35 order to be able to lock the fastener by means of the bolt or latch 13, this bolt being moved below the front end 7 of the spring 8. It will be quite evident from the present invention that due to the shape of the corresponding hook-shaped edges 1 40 and 6 that they will cause a centering action for the portions 3 and 5 at all times when engaged.

The visible portion of the fastener may be variously formed, as shown more particularly by Figs. 4, 5 and 6. The surface of the fastener may 45 be made ornamental, so that the actual object of the fastener is not apparent from its general appearance. The fastener may be made of plastic materials, for example artificial resin or the like. The method of production is very simple, so that the fastener costs very little to produce.

It will be evident from Fig. 2 of the drawing that each portion has a pair of stop faces one on each side of each right-angled section 1 and 55

6 and these stop faces contact with each other when the fastener is in closed position.

What I claim as new and desire to secure by Letters Patent is:

- 5 1. A fastener for handbags, garments and the like, comprising a pair of interengaging portions, each portion having approximately right-angle flanges as effective surfaces of engagement and an engaging face on one side of each flange, and
- 10 a spring secured in one of said portions at a point opposite its right-angle flange and extending to a free end toward said last mentioned flange to maintain the two right-angle flanges interengaged when the faces of the portions abut against
- 15 each other and to force and maintain the two portions together in closed position by the free end of the spring bearing against the other of said portions, each portion having a pair of stop faces one on each side of each right-angled flange

which stop faces contact with each other when the fastener is in closed position.

2. A fastener according to claim 1 in which one of the portions is provided with an actuating button and the spring is secured in the other portion. 5

3. In a fastener, a male portion, a female portion, a hooked edge to the said female portion, a hooked edge to the said male portion bent in opposition to the hooked edge on the said female portion and adapted to engage therewith when the fastener is closed, a spring holding the said hooked edges in engagement, and a bolt adapted to be moved under the free edge of the said spring to prevent disengagement of the said edges, the 10 line of engagement of the said edges being greater in length than the width of the fastener. 15

ALFRED BOENECKE.
